FIG. 4

FIG. 5

INVENTOR

Benedykt A. Kaszinski

BY
John J. Pacholski
ATTORNEY

UNITED STATES PATENT OFFICE.

BENEDYKT A. KASZINSKI, OF NEW YORK, N. Y.

HOE.

Application filed October 17, 1923. Serial No. 668,975.

To all whom it may concern:

Be it known that I, BENEDYKT A. KASZINSKI, a citizen of Poland, residing at New York, in the county of New York and State 5 of New York, have invented certain new and useful Improvements in Hoes, of which the following is a specification.

This invention relates generally to gardening implements, having particular reference to a novel construction for a hoe whereby the range of utility thereof may be increased, the invention having for an object to increase the efficiency and utility of the hoe.

15 For further comprehension of the invention, and of the objects and advantages thereof, reference will be had to the following description and accompanying drawing, and to the appended claims in which the various novel features of the invention are 20 more particularly set forth.

Fig. 1 of the drawing is a perspective view showing one embodiment of my improved hoe.

25 Fig. 2 is a detail transverse sectional view of the detachable blade.

Fig. 3 is a face view showing the blade of my improved hoe.

30 Fig. 4 is a transverse sectional view thereof taken on the line 4—4 of Fig. 3.

Fig. 5 is a fragmentary rear view of the blade.

Referring now to the drawing, my improved hoe as there disclosed comprises a 35 skeleton blade removably fixed to a number of prongs, removal of the blade permitting the implement to be used as a rake. The blade of the hoe is here numbered 20 and is of rectangular outline with teeth 22, formed 40 on the lower edge thereof, ribs 23 extending upward from said teeth along the back of the blade. The blade is here shown as of skeleton construction with holes or apertures 24 between the ribs 23. The prongs to 45 which the blade is attached are shown at 26 and project from a backing element 27 and are thickened in their upper portions as at 26' and these upper portions present at their forward edges downwardly projecting fingers 28 which are spaced forward from the lower portions of the prongs, thus forming

upwardly extending recesses or sockets to receive the top edge of the blade. Formed on the front face of the lower portion of each prong 26 a short distance below the bottom of the thickened upper portion is a lug 29, while the blade presents complementary openings such as 30 through which these lugs project when the blade is in position. The lugs 29 project a distance from the prong elements 26 corresponding to the thickness of the blades 20 so as to have their faces flush with the face of the blade, while the fingers 28 are spaced from the lugs a like distance, so as to permit of removal and replacing of the blade. In this space a flat strap 32 is placed and serves to hold the blade against removal, and this strap may be secured at opposite ends to the blade by means of the screws 33 or by any other means permitting of ready removal of the strap.

The prongs 26 extend downward only partially over the blade 20 while the ribs 23 are terminated short of the upper edge of the blade and have recesses or sockets such as 34 in their upper ends in which the pointed lower ends of the prongs engage, thus securely locking the blade against displacement, while at the same time permitting of its easy removal so that the implement may be used as a rake.

Having thus described my invention what I claim as new and desire to protect by Letters Patent of the United States is as follows:

1. A hoe comprising a handle and a blade, said handle having a series of prongs presenting upwardly extended sockets adapted to receive the top edge of the blade, said blade presenting sockets to receive the lower ends of the said prongs, and means for retaining said blade in position with the top thereof in the said upwardly extended sockets and the lower ends of the prongs in the sockets in the blade comprising a flat strip extending through said upwardly extended sockets and along the rear face of the hoe.

2. A hoe comprising a handle and a blade, said handle having a series of prongs presenting upwardly extended sockets adapted to receive the top edge of the blade, said

blade presenting sockets adapted to receive the lower ends of the said prongs, and means for retaining said blade in position with the top thereof in the said upwardly extended sockets and the lower ends of the prongs in the sockets in the blade, said means comprising lugs on the prongs engaging in ap-

ertures in the blade, and a flat strip extending along the upper edge of the blade and through the said upwardly extended sockets. 10

In testimony whereof I have affixed my signature.

BENEDYKT A. KASZINSKI.
